UNITED STATES PATENT OFFICE.

CHARLEY L. BEEMAN, OF RIVERTON, WYOMING, ASSIGNOR OF ONE-HALF TO R. P. KILE,
OF RIVERTON, WYOMING.

SHIPPING-TAG.

1,222,595.

Specification of Letters Patent. Patented Apr. 17, 1917.

Application filed May 26, 1916. Serial No. 100,086.

To all whom it may concern:

Be it known that I, CHARLEY L. BEEMAN, a native-born citizen of the United States, residing at Riverton, in the county of Fremont and State of Wyoming, have invented 5 new and useful Improvements in Shipping-Tags, of which the following is a specification.

This invention relates to improvements 10 in shipping tags and the like and particularly with reference to a fastening device for securing a string or wire to the tag, so that the same cannot become casually detached therefrom.

15 The invention consists in the features of construction, combination, and arrangement of devices, hereinafter fully described and claimed.

In the accompanying drawings—

20 Figure 1 is a perspective view of a tag provided with a string and a fastening device constructed and arranged in accordance with my invention.

Fig. 2 is an elevation of the same showing the reference side of the tag.

Fig. 3 is a sectional view on the plane indicated by the line 3—3 of Fig. 2.

Fig. 4 is a similar view on the plane indicated by the line 4—4 of Fig. 2.

30 The tag 1 may be of any suitable size and may be made of any suitable material and may be used for shipping or any other suitable purpose.

35 The string 2 is doubled and its bight is passed around one side of a sheet metal disk 3, which disk is provided on said side with peripherally projecting prongs 4 which are bent around the string and is also provided with prongs 5, which are driven 40 through the body of the tag and clenched on the reverse side thereof.

Copies of this patent may be obtained for five cents each, by addressing the "Commissioner of Patents, Washington, D. C."

A disk 6, of sheet metal or other suitable material is arranged on the reverse side of the tag and is held securely thereto by means of the clenched prongs 5. The 45 fastening disks greatly reinforce the tag as well as provide means for attaching the string or wire thereto. It will be observed and understood that my fastening devices secure the string or wire to the tag, without 50 the necessity of the formation of a knot of any kind, in the string or wire.

Having described the invention, what is claimed is:

1. In combination with a tag, a fastening 55 device thereon comprising a disk having prongs driven through and clenched on the bottom of the tag, said disk also having peripheral prongs and a doubled cord or the like arranged around the periphery of 60 the disk, the peripheral prongs of the latter being bent around said cord and offset from the plane of the disk.

2. In combination with a tag, a fastening 65 device thereon comprising a disk having prongs driven through and clenched on the bottom of the tag, said disk also having peripheral prongs and a doubled cord or the like arranged around the periphery of the 70 disk, the peripheral prongs of the latter being bent around said cord and offset from the plane of the disk, and a second disk on the reverse side of the tag and engaged and secured by the clenched prongs of the first 75 named disk.

In testimony whereof I affix my signature.

CHARLEY L. BEEMAN.
